UNITED STATES PATENT OFFICE.

JOHN H. PALMER, OF PHILADELPHIA, PENNSYLVANIA.

BUTTON-HOLE ATTACHMENT FOR SEWING-MACHINES.

SPECIFICATION forming part of Letters Patent No. 324,150, dated August 11, 1885.

Application filed January 9, 1885. (Model.)

To all whom it may concern:

Be it known that I, JOHN H. PALMER, of the city and county of Philadelphia, and State of Pennsylvania, have invented an Improvement in Button-Hole Attachments for Sewing-Machines, of which the following is a specification.

My invention has reference to button-hole attachments for sewing-machines; and it consists in certain improvements for vibrating the clamp or cloth-holder, rotating the feed-wheel, and deriving the necessary intermittent vibrations and rotations from the needle-bar of the sewing-machine, all of which is fully set forth in the following specification, and shown in the accompanying drawings, which form part thereof.

The object of this invention is to construct a simple form of button-hole attachments to sewing-machines adapted to attachment on any machine, and the parts of which may be nearly all stamped from sheet metal, thus reducing the cost to a minimum.

In the drawings, Figure 1 is a perspective view of a button-hole attachment embodying my improvements. Fig. 2 is a plan view of same. Fig. 3 is a sectional elevation of same on line *x x*. Fig. 4 is a plan view, and Fig. 5 an elevation, of the adjustable hinge for regulating the throw of the pawl for operating the intermittent feeding-wheel; and Fig. 6 is an elevation of the preferred way of forming the cam-wheel by which the necessary intermittent vibrations are derived from the reciprocation of the needle-bar.

The first feature of importance is a plan for converting the vertical reciprocating movement of a needle-bar into a horizontal reciprocating movement of a slide or bar from which the vibratory movement of the clamp is afterward obtained, and this is accomplished in the following manner, referring to the drawings herewith: The lever *A* and *A'* is made in two parts, having the fulcrum at *B*, and is provided with adjusting-screws at *A*², for the purpose of regulating the amount of vibration of the short arm *A'* of the said lever, which is connected by the pin *C* to the radius-lever *C'*, carrying the pawl *C'* that engages the ratchet-wheel *c*, the pawl *C'* being caused to move about the ratchet-wheel by means of the radius-lever *C'*. The ratchet-wheel *c* is securely at-

tached to the cam *D*, which has an uneven number of projections, *d*, and a corresponding number of depressions upon its outer edge, 55 the number of such projections and depressions being uneven, so that when the cam *D* is placed between the opposite rounded surfaces *e* of the slide or bar *E* and turned round upon its fulcrum-pin *f* the slide or bar *E* is 60 caused to reciprocate in the guides *F* on the base-plate *F'*. It is necessary that the reciprocation of the slide or bar *E* should be in proportion to the vibrations of the lever *A* and *A'* as one to two, and to secure this proportion 65 the number of teeth on the ratchet-wheel *c* is twice that of the projections on the cam *D*; and as the ratchet-wheel *c* is advanced in its rotation one tooth by each full vibration of the lever *A* *A'* it follows that the slide or bar *E* is 70 moved one part of its reciprocation only for each full vibration of the lever *A* *A'*. The cam *D* and the ratchet-wheel *c* are secured to a part of the base-plate *F'*, which is turned up at right angles and marked *E'*, which part is 75 a continuation of the base-plate and forms a guide for the reciprocating plate *E*.

The second part of my invention consists of means to vibrate the cloth-holder or clamp-lever, and is secured as follows: To the base-plate *F'* the lever *G* is pivoted by its fulcrum-pin *g*, and carries the movable short arm *g'*, which is secured thereto by the screw *H* and held in position by the guides *h*. The short arm *g'* is movable, so that the amount of vibration of the clamp bearing slides or levers *I* *Q*, with which the short arm *g'* of the lever *G* engages at *i*, can be varied. The lever *G* is passed through the slide or bar *E* at *e'*, and is actuated by it.

The third part of this improvement is a device for securing and regulating the intermittent rotation of a feed-wheel, which can either be toothed or in the form of a friction clutch mechanism, and I have designed the following arrangement of parts to accomplish the desired end. To the base-plate *F'* is secured the pin *l*, which serves as a fulcrum to the lever *L*, one end of which passes through the reciprocating slide or bar *E* at *l* and is actuated by it. The other end is loosely connected by the adjustable guides *m* *m'* to the pawl-bearing lever *M*, which has as its fulcrum the same pin *M'* upon which the feed-wheel *K*

rotates intermittently. The amount of such intermittent rotation can be varied by moving the guides m m' along the levers L and M, the upper guide, m , being provided with a clamp-screw, n , by which it can be retained in any desirable position upon the lever M, while the lever L is free to slide in the guide m' . The guides m and m' are provided with a common fulcrum-pin upon which they can both turn.

10 P is the cloth-clamp, and is connected to the lever Q, having a slot, Q', in which a pin and block, I', secured to the vibrating lever I, works; but the lever I is simply a vibrating lever, while the lever Q is a vibrating and reciprocating lever, its vibrations being imparted by the pin I' and a cam, I², and its reciprocations imparted by a cam, I³, which cams are secured to a feed-wheel, K; but in this application I do not lay any particular claim to the construction of these levers, the invention relating to the mechanism by which the proper motions are imparted to these levers.

15 In practice I prefer to construct the intermittent cam-wheel D as shown in Fig. 6, for in this construction the projections d operate upon the parts e of the sliding plate in a positive manner, so that it is impossible for the plate to move excepting at the right time, and then, too, in a most positive manner.

20 While I prefer the specific construction shown, I do not limit myself to the details thereof, as they may be modified in various ways without departing from my invention, and, if desired, the bottom of the plate F' may be provided with plate F², (see Fig. 1), which slides into the guides on the sewing-machine and secures the button-hole attachment where the needle-bar plate was formerly located.

25 40 In this application I do not claim anything set forth or shown in the patents to Mills, No. 305,624, of 1884, and No. 313,358, of 1885, or Gilbert, No. 306,604, of 1884.

Having now described my invention, what I claim as new, and desire to secure by Letters Patent, is—

1. In a button-hole attachment for a sewing-machine, a horizontal reciprocating plate, in combination with a vertical reciprocating needle-bar, cam mechanism, substantially as set forth, to reciprocate said plate, jointed lever mechanism, substantially as shown, by which the vertical reciprocations of the needle-bar are converted into horizontal reciprocations of the said plate, a cloth-clamp, lever mechanism therefor, and connecting devices, substantially as shown, connecting said horizontally-reciprocating plate with said lever mechanism, substantially as and for the purpose specified.

2. The cam D, having an uneven number of projections, d , having curved faces made concentric with the axis of the cam, so that

the working-faces are of sufficient length to allow for wear and loose play in the parts, in combination with a sliding plate, E, having two fixed points, e , working on the face of the cam and separated a distance substantially equal to the pitch diameter of the cam, the cloth-clamp, its operating-levers, substantially as set forth, mechanism and connecting mechanism, substantially as described, whereby the cloth-clamp-operating levers are operated by the reciprocating sliding plate, substantially as and for the purpose specified. 75

3. The cam D, having an uneven number of projections, d , having curved faces made concentric with the axis of the cam, so that the working-faces are of sufficient length to allow for wear and loose play in the parts, and a ratchet-wheel, c , secured to the cam and having twice as many teeth as the cam projections, and pawl mechanism to intermittently rotate said ratchet-wheel one tooth at a time, the cloth-clamp, its operating-levers, substantially as set forth, mechanism and connecting mechanism, substantially as described, whereby the cloth-clamp-operating levers are operated by the reciprocating sliding plate, substantially as and for the purpose specified. 80 85 90

4. The combination of the needle-bar with lever A, lever A', having stops A², lever C², having pawl C', ratchet-wheel c , cam D, sliding plate E, the cloth-clamp, its operating-levers, substantially as set forth, mechanism 95 and connecting mechanism, substantially as described, whereby the cloth-clamp-operating levers are operated by the reciprocating sliding plate, substantially as and for the purpose specified. 100

5. The combination of the needle-bar with lever A, lever A', having adjustable stops A², lever C², having pawl C', ratchet-wheel c , cam D, sliding plate E, the cloth-clamp, its operating-levers, substantially as set forth, mechanism 105 and connecting mechanism, substantially as described, whereby the cloth-clamp-operating levers are operated by the reciprocating sliding plate, substantially as and for the purpose specified. 110

6. The combination of reciprocating plate E, levers L M, adjustable connections m m' , a feed-wheel, and connecting mechanism by which the oscillations of the lever M rotate the feed-wheel, substantially as and for the purpose specified. 115

7. The combination of reciprocating plate E with lever G, adjustable part g', and pivoted cloth-holding levers, substantially as and for the purpose specified. 120

In testimony of which invention I hereunto set my hand.
